UNITED STATES PATENT OFFICE.

DUDLEY F. DILLIN, OF ALLIANCE, OHIO, ASSIGNOR, BY MESNE ASSIGNMENTS, TO THE
MCCASKEY REGISTER COMPANY, (INCORPORATED IN 1914,) OF ALLIANCE, OHIO, A
CORPORATION OF OHIO.

MANIFOLDING-BOOK.

1,122,870.

Specification of Letters Patent. Patented Dec. 29, 1914.

Application filed January 5, 1910. Serial No. 536,485.

To all whom it may concern:

Be it known that I, DUDLEY F. DILLIN, a citizen of the United States, residing at Alliance, in the county of Stark and State 5 of Ohio, have invented certain new and useful Improvements in and Relating to Manifolding-Books, of which the following is a specification.

The object of the invention is to provide 10 a pad comprising a series of triplicate sets of sales bills with a cover on the back bound together with the sales bills at one end and having an extension to fold over upon the sales bills at the other end, with transferring material on the back of the first bill of each set for making the duplicate copy, and with manifolding material on the upper side of the cover extension when folded upon the bills for making the triplicate copy 15 by inserting the extension as a stop-card between the first and second sets of sales bills, the triplicate bill being made of transparent paper for receiving the copy on its reverse side.

20 For the purposes of illustration, I have, in the accompanying drawings, shown and herein described one form of manifolding salesbook embodying my invention.

Figure 1 is a plan view of a manifold book or pad embodying my invention, the slips of the uppermost set being partially thrown back. Fig. 2 is a side elevation of the book or pad. Fig. 3 is a view at the front end of the pad showing the cover therefor in section. Fig. 4 is a perspective view of the pad, one set of slips being thrown back and the cover extension being broken away at one corner.

In the drawings, 1 indicates a manifolding pad or book comprising a plurality of sets of slips, each set consisting of an original slip 1^a, and manifolding slips 1^b, and 1^c, the latter slip being formed from tissue or transparent paper. Preferably, the under surface of the original slip 1^a, is provided with a transfer medium 1^d so that the entry is transferred to the slip 1^b.

2 indicates a covering for the pad 1. This covering comprises a back 2^a and an extension or front 2^b which is folded around or over the free ends of the sheets or slips 1^a, 1^b, and 1^c, as shown at 2^c. The slips 1^a, 1^b, and 1^c are all secured together and to the back 2^a by staples 3. The slips 1^a, 1^b, and 55 1^c are preferably weakened along a trans-

verse line 3^a slightly below the staples 3, in order that each slip or each set of slips may be detached from the pad 1 after an entry has been made thereon.

4 indicates a carbon sheet which is pasted 60 to and lies flat upon the upper surface of the front 2^b. The extension 2^b is preferably made slightly wider than the pad 1 in order that it may be easily grasped and operated, and the carbon sheet 4 is made slightly 65 smaller in width than the extension 2^b so that the fingers will not come in contact therewith in operating the extension 2^b. The under surface of the extension 2^b has preferably 70 printed thereon longitudinal and transverse 75 rulings to form suitable columns for the entry of the total amount of each sale.

In the operation of the pad the extension 2^b is inserted between the uppermost set of slips and the next lower set of slips, after 75 which an entry is made upon the original slips 1^a of the uppermost set of slips. The impression from the carbon 4 is made upon the lower surface of the slip 1^c, but as this slip is transparent, it may be read as though 80 made on its upper surface. When such entry has been made, one or more of the slips of the set may be detached. The extension 2^b may then be inserted below the next succeeding set of slips. 85

From the above description it will be seen that the front 2^b operates to form a hard smooth writing surface when entries are made on the original slips; that it operates as a support for every part and portion of the carbon or transfer sheet 4, thus preventing the latter from becoming torn or wrinkled; that it serves as a cover for the pad when not inserted between two sets of slips; and that it serves as a stop-card 95. to prevent impressions being made upon any of the manifolding slips that are below it. Further, by pasting the carbon sheet 4 directly upon the front 2^b, only one part is operated and only one operation is 100 required to manipulate the book in getting it ready for each succeeding entry.

It will be understood that by making one slip of each set of slips from tissue paper, the pad is materially reduced in height. 105

To those skilled or who become skilled in the art of making manifolding books of the class described, many alterations in construction and widely differing embodiments and applications of my invention will sug- 110

gest themselves, without departing from the spirit and scope thereof. My disclosures and the description herein are purely illustrative and are not intended to be in any sense limiting.

5 What I claim is—

1. A manifolding book comprising a series of sets of slips of paper, each set consisting of an original slip, a duplicate slip, and a triplicate slip, the latter slip being formed from transparent paper, a covering having a back and an extension, a carbon sheet secured flat to the upper surface of said extension, and the said extension being insertible between the triplicate slip of the set of slips and the original slip of the next or following set of slips, means for transferring matter written on the original slip to the duplicate slip of each set of slips, and means securing the slips of the said sets of slips to each other and to the back of the covering.

2. A manifolding book comprising a series of sets of slips of paper, each set consisting of an original slip, a duplicate slip, and a triplicate slip, the latter slip being formed from transparent paper, a covering having a back and an extension, a carbon sheet secured flat to the upper surface of said extension, and the said extension being insertible between the triplicate slip of the set of slips and the original slip of the next or following set of slips, means for transferring matter written on the original slip to the duplicate slip of each set of slips, and means securing the slips of the said sets of slips to each other and to the back of the covering.

25 In testimony whereof I affix my signature, in the presence of two witnesses.

30 DUDLEY F. DILLIN.
